R. E. POWELL

PROCESS FOR RECLAIMING DISTILLATION RESIDUES

Filed Feb. 25, 1925

RAYMOND E. POWELL
Inventor

By Attorney C. W. Straw

UNITED STATES PATENT OFFICE.

RAYMOND E. POWELL, OF HOUSTON, TEXAS, ASSIGNOR TO STANDARD OIL DEVELOPMENT COMPANY, A CORPORATION OF DELAWARE.

PROCESS FOR RECLAIMING DISTILLATION RESIDUES.

Application filed February 25, 1925. Serial No. 11,425.

This invention relates to the art of reclaiming distillation residues and more particularly such residues as are left in redistilling lubricating stocks which contain 5 naphthenic compounds. Reference is made to the process and apparatus described in the application of Coleman and Hughes, Serial No. 691,162, filed February 7, 1924. The present invention is a development therefrom, and comprises as an essential feature 10 the reduction of viscosity, fluxing, or dilution of the distillation residue before removing the naphthenic compounds. The material added to the residue may be gas oil, Diesel oil, tar from the operation of cracking 15 apparatus, or the like. All suitable materials of this character are included in the term fluxing agent, as used herein.

As described in application Serial No. 20 691,162, when lubricating stocks containing naphthenic acids are redistilled in the presence of caustic soda, or other sodium compound, a heavy residue comprising an intimate mixture of sodium naphthenate or other 25 naphthenates and high viscosity oil is left in the still. This residue will be referred to as caustic bottoms and the reclamation of oil from it will be described as illustrative of the invention. It is to be understood, however, 30 that the process is not limited to treatment of this particular type of residue.

In carrying out the present invention, I add a viscosity-reducing material or the like to the caustic bottoms and then flow the resulting mixture upon a stream of water. Undesirable constituents, especially naphthenic soaps, are dissolved in the water. Stratification and separation are then effected, as more fully described later.

40 I have found that fluxing the distillation residue results in better contact between the residue and the water. Consequently there is a more efficient removal of naphthenic soaps and the like.

45 The flux may be mixed with the caustic bottoms in any suitable way. For example, gas oil may be pre-heated, if necessary, and discharged into the line carrying the hot bottoms to the washing system or separator.

50 The gas oil should ordinarily be at 500° F.

or thereabout to prevent too much cooling of the bottoms.

Depending upon particular conditions, the temperature of the fluxed bottoms may vary between about 300° F. to 650° F. Ordinarily better separation is secured at the higher temperatures within this range. The amount of gas oil will also vary according to conditions. Ordinarily 25% by volume of gas oil is sufficient to produce a mixture of proper 60 viscosity. The mixing of the bottoms and flux may be carried out under pressure, usually less than 50 lbs. sq. in., in a fuel incorporator or other suitable apparatus. The pressure may be released before passing the 65 mixture into the separator.

Alternatively, cool gas oil may be pumped to a still receiving the bottoms, or into the pipe conveying the bottoms to the still. The temperature of the still may be maintained 70 at about 550 to 600° F., and steam sufficient to secure mixing and prevent coking may be injected. The fluxed bottoms are pumped from the still and discharged into the separator, preferably without much loss of temperature. The bottoms may be mixed with the flux and the mixture then passed to the still or other suitable apparatus.

When cracking coil tar or the like is the fluxing agent, it is generally desirable to use 80 about 50% of it by volume to obtain the desired viscosity.

A preferred method of operation will be described in connection with the accompanying drawing, in which the single figure is an 85 isometric view of one form of apparatus contemplated.

Referring to the drawings, numeral 1 denotes suitable apparatus, such as a still, into which bottoms and fluxing oil are introduced 90 respectively through pipes 2 and 3. Steam may be injected through line 4 and any vapors involved may be taken off through line 5. The necessary amount of heat is supplied to the still, so that the fluxed oil may 95 be taken off through pipe 6 at a suitable temperature, as described.

The fluxed oil then passes without much loss of heat into the trough 7 of settling tank 8. Water enters through pipe 9, which 100

is arranged to provide a stream of water receiving on its surface the fluxed oil from pipe 6. The pipe 6 preferably has a spray head or slotted-head discharge, so as to spread the fluxed oil over the water.

The trough 7 discharges into the settling tank 8, a dam 9' being provided to maintain a fixed water level in the trough, and an apron 10 to prevent currents at the point of discharge into the tank. The settling tank may vary considerably in its form and dimensions. An advantageous layout is illustrated in the drawing. The baffles 11, 12 and 13 are arranged in the tank in laterally staggered order so as to compel the contained liquids to travel very slowly and free from turbulence to the respective points of discharge. Valve-controlled draw-off pipes 14 and 15 are arranged at the bottom of the tank, and from a point near its top a draw-off pipe 16 leads to discharge into a second tank 17. Along the bottom of the second tank a suitable heating means is arranged, illustrated in the drawing, for instance, as 25 a steam coil 18. A valve-controlled draw-off pipe 19 is provided at the bottom of this tank and an adjustable swing draw-off pipe 20 at the top.

In tank 8 stratification takes place with the formation of an upper layer of oil and a lower layer of water containing naphthenates dissolved from the oil.

At the start sufficient water is supplied to the tank to bring the level up well to the top and after the feed of residuum is established and stratification has taken place, the lower layer is drawn off at such a rate as to allow an adequate accumulation of the upper layers, permitting suitable draw-off 40 thereof into the second tank 17. By proper regulation of the draw-off valves the process may thus be made to function in continuous manner, the stratification levels being maintained at relatively constant points. The oil layer and some naphthenic compounds pass over to the second tank, and here final stratification and separation allows of the withdrawing of the clean oil from the top by means of the swing pipe 20. From the bottom of the tank the naphthenic compounds, occurring here chiefly as naphthenates of the heavy metals, especially iron, are withdrawn for further treatment. This treatment may vary somewhat, but preferably comprises 55 subjecting the naphthenate mixture, it being in the form of emulsion, to the action of sulfuric acid. This serves to decompose the naphthenates and set free the naphthenic acid and the emulsified oil, and on settling 60 these constituents can be drawn off from the top and the sludge run to waste.

It will be understood, however, that the naphthenates of the heavy metals form such a minor component of the distillation residue 65 that in many cases it is not worth while sepa-

rating and treating them independently, but the separation may proceed along the main lines of division of the oil on the one hand and the water-soluble naphthenates on the other. The water-soluble naphthenates 70 may be suitably recovered from the water, as by salting out or by concentration, and these compounds are then available for various uses as desired.

If preferred, the stratification levels can 75 be so maintained that the emulsified heavy metal naphthenate layer may be drawn off from tank 8 and further separated, as mentioned in the foregoing, instead of being carried over into tank 17 and there separated; that is, the precise point at which the separation of the heavy metal emulsified naphthenate layer occurs is a matter of choice in operating detail.

It is preferred to provide a cover 21 for 85 at least a portion of settling tank 8, and to arrange a draw-off pipe, as 22, for vapors that may be evolved from the hot oil entering the settling tank. Ordinarily it is sufficient to cover the first compartment only, 90 as shown. In this way danger from the flashing or ignition of these vapors is obviated.

Various changes may be made in the described embodiments of the invention, within the scope of the appended claims, in which it is my intention to claim all novelty inherent in the invention as broadly as the prior art permits.

I claim:

1. Process of reclaiming a naphthenic distillation residue, which comprises adding a fluxing material comprising a hydrocarbon oil of viscosity less than that of said residue and of boiling range high enough to ensure 105 presence in liquid state thereto, discharging the fluxed residue while hot upon the surface of gently moving water, then retarding the flow and allowing stratification to take place, and separately withdrawing the oil 110 and the water containing dissolved naphthenic compounds.

2. Process of reclaiming a naphthenic distillation residue, which comprises mixing the residue with gas oil, discharging the 115 fluxed residue while hot upon the surface of flowing water, then allowing stratification to occur, withdrawing the water containing dissolved naphthenates from the bottom layer, further settling the upper layers, 120 withdrawing the oil from the top, and then withdrawing heavy metal naphthenates.

3. Process of reclaiming a distillation residue containing water-soluble constituents, which comprises mixing a fluxing agent 125 with a hot body of the residue, maintaining the heat of the mixture, discharging the hot fluxed residue upon the surface of a stream of water, allowing stratification to take place, and separately withdrawing the oil 130

and the water containing dissolved constituents.

4. Process of removing naphthenates from caustic soda bottoms, which comprises charging the bottoms while hot in a still, adding relatively cool gas oil in amount sufficient to flux the bottoms, heating the still to maintain the temperature of its contents, inject-

ing sufficient steam to mix the bottoms and gas oil, discharging the fluxed residue upon the surface of a stream of water, allowing stratification to take place, and separately withdrawing the oil and the water containing dissolved sodium naphthenates. 10

RAYMOND E. POWELL.
